UNITED STATES PATENT OFFICE.

WILLIAM L. MIGGETT, OF ANN ARBOR, MICHIGAN.

OILER.

No. 862,576.

Specification of Letters Patent.

Patented Aug. 6, 1907.

Application filed July 23, 1906. Serial No. 327,288.

To all whom it may concern:

Be it known that I, WILLIAM L. MIGGETT, a citizen of the United States, residing at Ann Arbor, county of Washtenaw, State of Michigan, have invented a certain new and useful Improvement in Oilers; and declare the following to be a full, clear, and exact description of the same, such as will enable others skilled in the art to which it pertains to make and use the same, reference being had to the accompanying drawings, which form a part of this specification.

My invention relates to oilers, and consists in the improvements hereinafter described and pointed out in the claims.

In the accompanying drawings:—Figure 1, is a sectional elevation of a device embodying my invention. Figs. 2, and 3, are details illustrating the operation of the apparatus for adjusting the rate of feed. Fig. 4, is a plan view of an oiler embodying my invention. Fig. 5, is a section on the line 5—5 Fig. 1. Figs. 6, 7, 8, and 9, are sections on the line 6—6 Fig. 1; a portion of the lever O by which said valve is adjusted to different angular positions being also shown, and the valve being shown in its different operative positions. Fig. 10, is a vertical section on an enlarged scale through the axis 25 of the feed valve in the position shown in Fig. 9, showing parts adjacent to the feed valve in section.

Referring to Fig. 1, C is the usual glass cylinder used in oil cups. A is a base, and B a cap. The base A and cap B are drawn together by a coaxial tube D united to the base at its lower end, and provided with a nut E at its upper end, thus closing the ends of the cylinder C. The nut E may be screwed down on the threads on the tube D against the cap B, or against a washer on said cap.

35 In the base A is formed, coaxial with said base and the cylinder C, a cavity bounded by conical walls e. This cavity opens by an aperture a through one of its walls to the interior of the cylinder C, which cylinder with the base and cap attached, as hereinbefore described, forms a reservoir for oil.

b is an aperture axially in line with, and opposite to, the aperture a. The aperture b opens to the exterior of the base A, except that in its outer end is a nipple X, which forms a means of communication to a source of 45 oil supply, not shown in the drawings. The conical walls c diverge downwardly.

L is the feed valve. This is formed with conical walls adapted to fit against the walls c.

e is a vertical passage in, and coaxial with, the 50 valve L.

f, f, are passages through the valve L, at right angles to the passage e, and communicating with said passage. g, h, are other passages in the same plane as the passages

f, f, but located at different angles and extending from the periphery of the valve L to its center. All the passages f, f, g, h, communicate with the upper end of the passage e. There is a conical valve seat d formed at the upper end of the passage e.

M is a tube coaxial with the cylinder C and valve L, rigidly connected to said valve at its lower end. The tube M extends through the cap B.

O is a lever arm connected to the tube M at its upper end so as to be capable of moving longitudinally with reference to said tube, but restrained from angular movement relative thereto.

N is a milled nut having screw threads engaging screw threads at the upper end of the tube M. The nut N is located above the lever arm O. By screwing down upon the nut N the tube M is drawn upward and the valve L drawn firmly against its seat.

P is a hardened steel conical valve adapted to seat upon the valve seat d to close the upper end of the passage e.

R is a rod extending axially in line with the valve B, and coaxial with the cylinder C through, and above, the upper end of the tube M.

Q is a sleeve adapted to fit and slide in the tube M, and to form a piece joining the valve P, and rod R, which are fixed to said sleeve.

V is a packing gland surrounding the rod R, and U is packing material above said gland.

T is a nut having a milled head, and provided with exterior screw threads engaging the interior screw threads in the upper end of the tube M. The nut T forms a second gland for holding the packing material U.

W is a helical spring resting at its lower end against the sleeve Q, and at its upper end against the gland V. The packing material U is compressed between the gland V and the nut T to form a tight joint.

S is a cam lever pivoted to the upper end of the rod R and provided with two cam faces adapted to engage the top of the nut T to draw upward on the rod R, lifting the valve P from its seat different distances when said lever is turned to different positions, as indicated in Figs. 1, 2, and 3, to cause the different faces to engage said nut.

F is a downward extension from, or an attachment to, the base A, adapted to serve for a means of attaching the oiler in position. There is an axial passage through the projection F from the passage e to the delivery end of said projection. Between its ends the projection F is cut away upon opposite sides as indicated in Fig. 5. Toward the upper end of the projection F is an interior bearing surface supporting the packing ring J.

H is a nut having a passage through it and having ex-

terior screw threads engaging interior screw threads in the projection F, toward the lower end thereof. The nut H is provided with a bearing surface supporting a packing ring J¹.

5 G is a glass cylinder, its upper end resting against the packing ring J¹. By turning the nut H, the cylinder G is forced firmly against its packing rings, so that tight joints are formed at the end of said cylinder.

Y (Fig. 4) indicates an opening by which the cylinder 10 C may be supplied with oil from a can. 1, 2, 3, 4, in said figure indicate notches in the cap B, into which a spring pawl or detent on the end of the lever O engage at the different operative positions. The reference numerals 1, 2, 3, 4, may, therefore, be used to indicate 15 these different operative positions of the lever O and valve L.

Z, is a passage-way formed obliquely through the valve L. The lower end of said passage-way opens at the lower end of the passage e, and the upper end of said 20 passage is adapted to be put into communication with the aperture a when the valve L is turned to the position indicated in Fig. 9.

The operation of the above described device is as follows:—The nipple X is connected with a source of oil 25 supply. When the lever O is turned to position 1, as indicated in Fig. 4, the passages f, f, put the apertures a and b into communication, and the oil runs from the source of supply into the cylinder C to fill the reservoir of the oiler. When the lever O is put into position 2 30 (Fig. 4) the valve L is in the position indicated in Fig. 7, in which case the aperture b is closed, shutting off the supply of oil, and the passage h communicates with the aperture a, so that when the valve P is raised, oil will flow from the reservoir of the oiler through the 35 passage e to the place of application. The rate of feed may be observed by looking through the glass of the cylinder G. When the lever O is turned to position 3 (Fig. 4) the valve L is in the position indicated in Fig. 8, in which the passage h puts the aperture b into communication with the passage e when the valve P is 40 raised, so that oil may flow from the source of supply directly to the place of application, without filling the reservoir of the oiler. When the lever arm O is turned to position 4 (Fig. 4) the valve L has the position indicated in Fig. 9, and also shown in Fig. 10, in which the 45 source of supply is put into communication with the point of application through the aperture b, passages g and e, and at the same time the passage Z communicates with the aperture a, so that the reservoir of the oiler is 50 in communication with the point of application of the oil. Thus, in this position, two kinds of oil can be fed at once, one from the reservoir through the passage Z, and the other from the source of supply through the passage e.

55 In the position of the lever S, shown in Fig. 1, the valve P is closed upon the conical seat d, held thereto by the spring W, and the passage e is thereby closed. When said lever is turned to the position shown in Fig. 2, the rod R is drawn upward, raising the valve P 60 slightly from its seat, and opening the passage e. When the lever S is turned to the position shown in Fig. 3, the valve P is drawn a considerable distance from its seat, leaving the passage e wide open. This latter may be

called the emergency position, a position for feeding oil rapidly under unusual circumstances, such as to supply a hot bearing.

It will be observed that with the various utilities above pointed out, the apparatus has the appearance of an ordinary oil cup.

The valve L is made of brass or other soft material, so 70 that the valve seat d is of such soft material. The valve P is of hardened steel. It is a small piece of metal, and can be properly tempered or removed and replaced.

If there is a pressure upon the oil supply, the oil may be fed from said supply, as required, and without danger of leakage.

What I claim is:—

1. An oiler, provided with a reservoir, a passage communicating with said reservoir, a passage adapted to communicate with a source of oil supply, and a delivery passage, and means for placing the oil supply passage in communication with said reservoir or with said delivery passage.

2. An oiler, provided with a reservoir, a passage leading to said reservoir, a passage adapted to be connected with a source of oil supply, and a delivery passage, and means for placing said delivery passage in communication with the passage to said reservoir or with the supply passage.

3. An oiler, provided with a reservoir, a passage leading to said reservoir, a passage adapted to be connected with a source of oil supply, and a delivery passage, and means for placing said delivery passage in communication with the passage to said reservoir or with the supply passage, and for connecting and disconnecting the supply passage to 95 the reservoir.

4. An oiler, provided with a reservoir, a passage leading to said reservoir, a passage to a source of oil supply, and a delivery passage, and a valve adapted to be controlled from the outside of said oiler provided with passages 100 adapted to put the various passages in the oiler into communication with each other, as described.

5. The combination of a valve, a valve stem leading from said valve, walls surrounding said valve stem, a gland V surrounding said stem and adapted to slide longitudinally thereof, a spring acting against said valve stem and said gland, packing material within said surrounding walls on the opposite side of said gland to said spring, and a stop to prevent the movement of said packing material.

6. The combination of a valve, a valve stem leading from said valve, walls surrounding said valve stem, a gland V surrounding said stem and adapted to slide longitudinally thereof, a spring acting against said valve stem and said gland, packing material within said surrounding walls on the opposite side of said gland to said spring, and an adjustable stop to prevent the movement of said packing material.

7. The combination of a valve, a valve stem leading from said valve, walls surrounding said valve stem, a gland V surrounding said stem and adapted to slide longitudinally thereof, a spring acting against said valve stem and said gland, packing material within said surrounding walls on the opposite side of said gland to said spring, an adjustable stop to prevent the movement of said packing material, and means acting against said adjustable stop 125 to lift said valve.

8. An oiler, provided with a reservoir for containing oil, a passage way located toward the bottom of said reservoir communicating therewith, a passage way located toward the bottom of said reservoir and adapted to be put in communication with a source of oil supply, and a delivery passage combined with a valve located near the bottom of said reservoir and adapted to control said passages, a tubular stem to said valve extending through a wall of said reservoir, means for adjusting said tubular stem longitudinally, and means for turning said tubular stem.

9. An oiler, provided with a reservoir, a passage leading

to said reservoir, a passage adapted to be put into communication with a source of oil supply combined with a valve having a delivery passage therein, said valve being adapted to control the passage to the reservoir and the 5 passage adapted to be put into communication with the source of supply, a valve adapted to control said delivery passage, and means for adjusting the position of said last named valve from the outside of the oiler, and means for operating the first named valve from the outside of the 10 oiler.

10. The combination of a valve P of hard metal, a valve seat of soft metal, a valve stem R, and a sleeve joining said valve and stem.

In testimony whereof, I, sign this specification in the presence of two witnesses.

WILLIAM L. MIGGETT.
